CLAIM

The ornamental design for a container for consumable goods, as shown and described.

DESCRIPTION

FIG. 1 is a perspective view of a container for consumable goods.

FIG. 2 is a front view of the container of FIG. 1.

FIG. 3 is a rear view of the container of FIG. 1.

FIG. 4 is a side view of the container of FIG. 1.

FIG. 5 is a top view of the container of FIG. 1.

FIG. 6 is a bottom view of the container of FIG. 1.

FIG. 7 is a perspective view of the container of FIG. 1 arranged in an opened condition.

FIG. 8 is a front view of the container of FIG. 7.

FIG. 9 is a side view of the container of FIG. 7; and,

FIG. 10 is a top view of the container of FIG. 7.

The broken line portion of the figure drawings is included to show unclaimed subject matter only and forms no part of the claimed design.
